ABSTRACT OF THE DISCLOSURE

A rock drill tool retainer wherein the retainer is held in any one of several desired positions relative to such tool by a resiliently deformable bushing engaging a rotatable shaft having flat surfaces thereon within an opening having complementary flat surfaces therein.

To those familiar with the field of rock drilling and the operation of other power operated percussive tools it is well known to provide a drill steel retainer which allows freedom of rotation to the drill steel and a limited amount of freedom for axial movement of the drill steel while preventing accidental disengagement of the drill steel from the rock drill or forcible ejection of the drill steel from the rock drill during operation thereof. In general such retaining devices are in the form of a fork having a U-shaped opening larger than the diameter of the drill steel but smaller than the diameter of a collar on the drill steel. Such a fork is normally mounted so as to be resiliently held in an engaged position while at the same time being movable by external force into a disengaged position so that the drill steel may be changed or removed for inspection and after being reinserted in the rock drill the above described fork is biased into the former engaged position to maintain the drill steel in operative position within the rock drill.

The use of the fork as a retainer has been satisfactory and means devised for maintaining the fork in the engaged and disengaged position, respectively, have served the purpose but have been unsatisfactory by reason of requiring a multiplicity of parts and because of too rapid wearing out caused by metal-to-metal contact coupled with severe vibratory conditions and further aggravated by dust and other forms of grit attendant upon the operation of rock drills and other power operated percussive tools.

The retaining device of this invention comprises a fork portion as above described forming the central portion of a stirrup shaped support element having arms, spaced apart and parallel to each other, extending from the forked portion rearwardly along opposite side surfaces of a rock drill front head and having in the leg portions coaxial openings. A square shaft or pin is rigidly removably secured in the two openings and extends in spaced relationship through a square or otherwise noncircular opening extending transversely through the front head of the rock drill. Between the square shaft and the square opening a resilient bushing, having an internal opening of the same shape as the exterior of the shaft and an external surface of the same shape as the interior of the front head transverse opening, fills the space between the shaft and the transverse opening. With a square shaft fitting the formed opening in a resilient bushing and with proper orientation of the square with respect to the rearwardly extending arms of the stirrup shaped retainer support element, the formed portion will be held in the engaged position relative to the collared drill steel. Since the shaft is square and mounted in a square opening in the resilient bushing, a rotative biasing force applied to the fork portion of the support element will cause the shaft to rotate within the resilient bushing until after

rotation of something more than 45° of rotation the squares will be approaching normal registration and the support element will snap into a new position 90° rotated from its original position and constrained to stay in this now disengaged position by the action of the resilient material upon the square shaft. It is therefore an object of this invention to provide a new and improved steel retaining device which is easy to operate, long wearing, and comprises a minimum number of relatively simple parts requiring no highly precise machining and readily replaceable without special tools should replacement become necessary.

This and other objects and advantages of this invention will be more readily apparent upon consideration of the following description and drawings in which:

FIG. 1 is a top plan view of a rock drill constructed according to the principles of this invention;

FIG. 2 is an enlarged fragmentary sectional view taken substantially on line 2—2 of FIG. 1;

FIG. 3 is a partially sectional view taken substantially on line 3—3 of FIG. 2;

FIG. 4 is a view similar to FIG. 2 with the components thereof rotated into different relative positions, including broken line representations of still other positions;

FIG. 5 is a fragmentary side elevational view of a portion of the rock drill of FIG. 1 on the enlarged scale of FIGS. 2 through 4;

FIG. 6 is a view taken substantially on line 6—6 of FIG. 3.

In FIG. 1 there is shown a rock drill of a type well known in the art generally indicated at 10 and comprising a back head 12 to the left as seen in FIG. 1, a body portion 14 and a front head portion 16 to the right as viewed in FIG. 1. For purposes of description the direction to the right in FIGS. 1 through 5 will be designated as a forward direction while the direction to the left will be taken as the rearward direction consistent with the usage well established in the field of rock drilling machinery as evidenced by the accepted names of the back head 12 and front head 16. The back head 12 is provided with an air inlet 18 to be connected to a source of compressed air (not shown) and suitable valving to provide compressed air for reciprocation of a hammer piston within the body portion 14 for percussively actuating a collared drill steel 20 of a type well known in the art slideably received within an internally polygonal opening 17 in the front head 16 for percussive and intermittent rotative actuation in a known manner.

The drill steel 20 is an elongated member extending forwardly to form, or be connected to, a suitable drill bit engaging a work surface (not shown) and extends rearwardly within the front head 16 a suitable distance to be percussively acted upon and intermittently rotated by the hammer piston in a well known manner. The drill steel 20 normally has a given diameter polygonal cross section with a collar portion 21 of larger diameter formed at a point intermediate its ends to determine the depth to which the rearward portion of the drill steel 20 shall be slideably received in the opening 17 for the above described actuation.

The front head 16 is provided with a downwardly extending, generally rectangular boss portion 22 extending across the front head portion 16 below the steel receiving opening 17 and having a longitudinal central axis A—A contained in a plane normal to the longitudinal central axis of the drill steel 20. An opening having flat internal surfaces, shown as the square opening 24, coaxial with the boss portion 22, extends therethrough and is provided with a mating bushing, such as the square bushing 26, of readily deformable resilient material such as urethane, soft rubber, neoprene, or the like, having a complementary opening, such as the square opening 28.

coaxial with the boss portion 22 and extending therethrough. The material of the bushing 26 must be soft and readily deformable but highly resilient so that after being compressed and displaced (as hereinafter described) it will strongly tend to return to its original shape and size. Furthermore for best results the bushing 26 is made somewhat larger than the opening 24 so that the bushing 26 is compressed at installation.

The front head 16 is further provided with a stirrup shaped drill steel retaining member 30 having a transversely extending central portion 32, spaced forwardly from the front head 16, and having rearwardly extending arm portions 34 spaced apart a sufficient distance to slideably engage the end portions of the boss 22 and long enough to extend rearwardly beyond the opening 24 in the boss 22. The central portion 32 of the retaining member 30 is provided with an inverted U shaped opening 36 (see FIG. 6) having leg portions 37 spaced apart by a distance somewhat greater than the diameter of the drill steel 20 but somewhat less than the diameter of the enlarged collar portion 21 so that the drill steel is free to slide axially within the limits imposed by the legs 37 of the central portion 32 and the front surface of the front head 16 and is likewise free to rotate within the opening 36 of the central portion 32.

Each of the arm portions 34 is provided with an opening 38 extending therethrough along the common axis A—A and cross bored as at 41. An elongated square pin or shaft 40, having a transverse bore 39 in each end portion normal to the axis A—A, is rigidly removably secured in the openings 38 in the arm portions 34 as by drive pins 42 engaged with opposite ends of the cross bores 41 and bores 39 in the end portions of the shaft 40, or by any other suitable retaining means rigidly securing the shaft 40 in the arm portions 34 for rotation therewith.

The shaft 40 is sized to cause some compression of the material of bushing 26 when inserted in the opening 28 and is thus firmly but resiliently held in a given position relative to the boss portion 22 with no metal to metal contact therebetween.

Operation of the retaining means 30 of this invention begins with the retainer and associated members positioned as shown in FIG. 2 with the drill steel being prevented from accidental disengagement with the rock drill 10, or forceful ejection therefrom in operation of the rock drill 10, in a well known manner by the instrumentality of the legs 37 engaging the collar 21 whenever the drill steel is disengaged from the work surface which normally holds the drill steel and prevents it from being propelled in the forward direction.

With suitable orientation of the square openings 24 and 28 relative to the cross bores 39 the retaining means 30 will be resiliently held in the locking position shown in FIG. 2 until it is desired to remove the drill steel for sharpening, replacement or other reason. A biasing force tending to rotate the retaining means 30 in a counterclockwise direction, as viewed in FIG. 2, will cause the bushing 26 to be deformed progressively against the tendency of the bushing 26 to retain its original shape until the position 30' (shown in solid outline in FIG. 4) is reached after approximately 45° counterclockwise rotation from the original position shown in FIG. 2. At this position indicated as 30' the opening 28 will be distorted into the shape 28' shown in FIG. 4 with the resilience of the bushing 26 providing equally balanced forces tending to return the retaining means 30 to its original locking position or to rotate the retaining means 30 further in the counterclockwise direction to a released position 30" rotated 90° counterclockwise from the original position 30. After such 90° rotation the retaining means 30 will be held in the released position 30" by the tendency of the bushing 26 to remain in its original shape since both of the square openings and the square shaft 40 will again be oriented as originally shown in FIG. 2. After the drill steel has been removed and replaced a clockwise

biasing force applied to the retaining means 30 in the position 30" will return it to the position 30' after which a slight further motion will cause the retaining means 30 to snap into position as shown in FIG. 2 with the tendency of the bushing 26 to maintain its original shape again resiliently but firmly maintaining the retaining means 30 in the desired position.

The advantages resident in the retaining means of this invention arise from:

(1) The provision of a completely resilient mounting for the shaft 40 relative to the rock drill 10 with no metal-to-metal contact under the severe vibratory conditions present during operation of the rock drill 10 resulting in lower rate of wear and less metal fatigue;

(2) The non-rigid but firmly resiliently biased positioning of the central portion 32 with the U-shaped opening extending closely above and alongside the drill steel 20 to prevent accidental disengagement of the drill steel 20 from the rock drill 10 with the attendant advantage of yieldably restraining the drill steel so that should the drill steel strike the legs 37, the retainer 30 can move in any direction necessary to relieve stresses which might otherwise be applied to the drill steel if a more solidly mounted retainer were used, as in structures of the prior art, resulting in increased drill steel life;

(3) The very limited number of parts necessary to accomplish the purpose of retaining the steel while resiliently maintaining the retaining member 30 in the engaged or disengaged positions giving lower production costs;

(4) The absence of any requirement for high precision machine work since no metal to metal rotating or sliding fits are required again reducing costs; and

(5) The ease with which the device of this invention can be assembled without need for special tools or skills.

It is to be noted that although the openings 24 and 28 as well as the shaft 40, mating therewith, have been described as square in cross section they are actually shown in the drawings as having cross sections which are squares with clipped corners since this is a shape of opening and shaft more readily produced than a true square and free of sharp corners either internal or external which would have a stress concentration effect tending to weaken the material where such corners occur. In any case adjacent flats on the shaft must be connected in some manner that avoids a sharp edge which could cut the resilient bushing instead of deforming it as desired.

It is further to be noted that although the cross sections of the openings and shaft are shown as squares having clipped corners such openings and shaft can be made in any non-circular shape as for instance hexagonal or partly round with flat sided portions at a suitable angle to each other. For example, if the openings and shaft each have two flats defining one ninety degree dihedral angle, respectively, this would give a preferred orientation for locking and a released position after 90° of rotation, wherein the locking position included matching of all flats, while the released position was maintained by mating only one flat on the shaft with one flat in each complementary opening.

A preferred embodiment of the tool retainer of this invention having hereinbefore been described and shown it is to be realized that variations in the size, shape and position of the various parts can be made without departing from the broad scope of this invention. It is therefore respectfully requested that the invention herein disclosed be interpreted as broadly as possible and limited only by the claims appended hereto.

What is claimed is:

1. In a tool retainer for retaining a collared drill steel in a percussive tool driver body, the tool retainer having two arm portions connected by a bight portion shaped to partially encompass such a collared drill steel when in a locked position, portions of said arm members remote from said bight portion being rigidly secured to

spaced portions of a shaft transversely disposed with respect to said collared drill steel and rotatably mounted in an opening in said body for rotation of said tool retainer between locked and unlocked positions, the improvement comprising: said shaft having at least one flat peripheral surface thereon and said opening having at least one flat surface therein complementary to said flat surfaces of said shaft, and a deformably resilient bushing occupying the space within said opening and external to said shaft, said flat surfaces respectively opposable to each other in selected positions of rotation of said shaft with respect to said tool driver body to alternatively maintain said tool retainer in a desired one of said locked and unlocked positions.

2. In a tool retainer for retaining a collared drill steel in a percussive tool driver body, the tool retainer having two substantially parallel arm portions connected by a bight portion shaped to partially encompass such a collared drill steel when in a locked position, the end portions of said arm members, remote from said bight portion, being rigidly secured to end portions of a shaft transversely disposed with respect to said collared drill steel and rotatably mounted in an opening in said body for rotation of said tool retainer between locked and unlocked positions, the improvement comprising: said shaft having substantial flat peripheral surfaces thereon and said opening having flat surfaces therein complementary to said flat surfaces of said shaft and a deformably resilient bushing occupying the space within said opening and external to said shaft, said flat surfaces respectively opposable to each other in selected positions of rotation of said shaft with respect to said tool driver body to maintain said tool retainer in a desired one of said locked and unlocked positions.

3. A tool retainer as specified in claim 2 wherein said shaft is polygonal in cross section and said opening has a complementary polygonal cross section.

4. A tool retainer as specified in claim 2 wherein said shaft is of substantially square cross section for at least a major portion of the shaft length and said deformable bushing is formed with a hollow substantially square cross section throughout the length thereof.

5. A tool retainer as specified in claim 4 wherein said shaft and said opening are sized to cause substantial compression of said bushing when assembled in coaxial and axially overlapping relationship.

10 6. A tool retainer as specified in claim 4 wherein said shaft end portions have cross bores and said arm end portions are removably secured to said shaft end portions by drive pin means received in said cross bores.

15 7. A tool retainer as specified in claim 2 wherein said shaft has at least two of said flat surfaces thereon forming a dihedral angle of approximately 90°.

20 8. A tool retainer as specified in claim 7 wherein adjacent ones of said at least two flat surfaces are connected by a substantially planar surface forming obtuse angles with both of said adjacent surfaces.

25 9. A tool retainer as specified in claim 7 wherein adjacent ones of said at least two flat surfaces cooperating with flat surfaces in said opening determine at least two preferred positions of said tool retainer relative to said tool driver body with an angle of approximately 90° between said preferred positions.
